United States Patent Office.

MORTON JUDD, OF NEW HAVEN, CONNECTICUT.

Design No. 3,795, dated December 21, 1869.

DESIGN FOR A WARDROBE-HOOK.

The Schedule referred to in these Letters Patent and making part of the same.

To all whom it may concern:

Be it known that I, MORTON JUDD, of New Haven, in the county of New Haven, and State of Connecticut, have invented a new Design for a Wardrobe-Hook; and I do hereby declare the following, when taken in connection with the accompanying drawing, to be a full, clear, and exact description of the same, and which said drawing constitutes part of this specification, and represents a side view.

This invention relates to a design for the article known to the trade as wardrobe-hooks, especially relating to a double hook, or coat and hat-hook.

The coat-hook extends from the base downward, and curved to form the hook, the hat-hook being a straight-headed pin, extending from the base, and on the reverse or back side of the base, a spike is formed to aid in the attachment of the hook, all as shown in the accompanying photographic illustration.

I claim, as my invention—

The design for wardrobe-hook, as shown.

MORTON JUDD.
